United States Patent Office

Des. 180,959
Patented Sept. 10, 1957

180,959

COVER FOR A STEPLADDER OR THE LIKE

Linden M. Roberdeaux, Toledo, Ohio

Application February 6, 1956, Serial No. 40,043

Term of patent 7 years

(Cl. D15—8)

Fig. 1.

Fig. 2.

Fig. 1 is a perspective view of a cover for a stepladder or the like showing my new design; and

Fig. 2 is an underside view, thereof.

I claim:

The ornamental design for a cover for a stepladder or the like, substantially as shown.
